GOLF CLUB HEAD

Leo C. Driscoll, 109 Pleasant St., Dumont, N.J. 07628

Filed Mar. 12, 1968, Ser. No. 10,930

Term of patent 14 years

U.S. Cl. D34—5

Int. Cl. D21—03

FIG. 1 is a front view of a golf club head showing minute design;

FIG. 2 is a rear view thereof;

FIG. 3 is a side view thereof as seen looking from the left of FIG. 1;

FIG. 4 is a side view thereof as seen looking from the right of FIG. 1; and

FIG. 5 is a top view thereof as seen looking down at FIG. 1.

I claim:

The ornamental design for a golf club head, as shown.
